CLAIM

I claim the ornamental design for a drink bottle cap, as shown and described.

DESCRIPTION

FIG. 1 is a perspective view of a drink bottle cap showing the design of the present disclosure with the cap's drink spout in a stowed configuration.

FIG. 2 is a perspective view of a drink bottle cap showing the design of the present disclosure with the cap's drink spout in a dispensing configuration.

FIG. 3 is a top plan view of the cap of FIG. 1.

FIG. 4 is a top plan view of the cap of FIG. 2.

FIG. 5 is a side elevation view of the cap of FIG. 1, with the other side view being a mirror image thereof.

FIG. 6 is a side elevation view of the cap of FIG. 2, with the other side view being a mirror image thereof.

FIG. 7 is a front elevation view of the cap of FIG. 1.

FIG. 8 is a front elevation view of the cap of FIG. 2.

FIG. 9 is a rear elevation view of the cap of FIG. 1; and, FIG. 10 is a rear elevation view of the cap of FIG. 2.

The broken line(s) shown in the drawings are for illustrative purposes only and form no part of the claimed design.

The bottom and internal construction of the cap form no part of the claimed design.

The shading lines shown in the drawings represent the three-dimensional contour of the design, and are not intended to indicate surface decoration.

Portions of the cap that are not shown in the drawings form no part of the claimed design.
